CLAIM

The ornamental design for a footwear as shown and described.

DESCRIPTION

FIG. 1 is an outer side view of a footwear;

FIG. 2 is an inner side view thereof;

FIG. 3 is a front view thereof;

FIG. 4 is a back view thereof;

FIG. 5 is top view thereof; and,

FIG. 6 is a bottom view thereof.

The elements shown in FIGS. 1-6 that are overlaid with a white transparent mask bounded by broken lines represent portions that form no part of the claimed design.
